INDEPENDENTLY SPRUNG FRONT WHEEL

Philip E. Mathews, Plainfield, N. J., assignor to
 Mack Manufacturing Corporation, Long Island
 City, N. Y., a corporation of Delaware

Application August 6, 1937, Serial No. 157,671

3 Claims. (Cl. 267—57)

The present invention relates to independently sprung wheels and embodies, more specifically, an improved mounting by means of which wheels may be mounted independently upon vehicle frames. In this connection, the present invention relates generally to the subject matter shown and described in applicant's copending applications Serial No. 757,089, filed December 12, 1934 for "Independently sprung front wheel" and Serial No. 48,802, filed November 8, 1935 for "Independently sprung front wheel".

The invention is particularly useful in connection with wheel mountings of the above character wherein torsion springs are utilized to cushion the movement of the wheel with respect to the frame, and the present invention contemplates the provision of an independent wheel mounting by means of which adequate vertical movement of the wheel is permitted while providing a mechanism which is sufficiently strong to withstand the shocks and stresses to which it is subjected during operation.

An object of the invention, accordingly, is to provide an independently sprung wheel mechanism of an improved character wherein means is provided to prevent excessive vertical movement of the wheel. A further object of the invention is to provide a mechanism of the above character wherein torsion springs are incorporated to cushion relative vertical movement of the wheel with respect to the frame, supplementary mechanism being provided to reinforce the wheel mounting mechanism against stresses subjected thereto in a direction parallel to the vehicle frame.

Further objects of the invention will be apparent as it is described in greater detail in connection with the accompanying drawings, wherein:

10 Figure 1 is a view in front elevation, partly in section, on the line 1—1 of Figure 2, of an independently sprung front wheel, constructed in accordance with the present invention.

15 Figure 2 is a view in section taken on the line 2—2 of Figure 1 and looking in the direction of the arrows.

Figure 3 is a plan view of the mechanism shown in Figure 1.

20 Figure 4 is a view in front elevation similar to Figure 1 and shows a modified form of the invention.

Figure 5 is a view in side elevation of the mechanism shown in Figure 4.

25 Figure 6 is a view in section taken on the line

6—6 of Figure 5 looking in the direction of the arrows.

Figure 7 is a plan view of the device taken in section along lines 7—7 of Figure 1 looking in the direction of the arrows.

Referring to the construction shown in Figures 1, 2 and 3, the side frame channel member of a vehicle is shown at 10 and a wheel to be independently mounted thereon is indicated at 11 by the dot and dash lines in Figure 1. This wheel is adapted to be mounted upon a cylinder 12 which is carried by a knuckle member 13 which serves as a steering pivot. This knuckle member is adapted to be mounted upon the frame member 10 by means of upper and lower pivot pins 14. Upper and lower pantograph arms 15 and 16, respectively, are formed with bifurcated extremities 17 in which the pivot pins 14 are received.

The other ends of arms 15 and 16 are secured to torsion springs 18 and 19, respectively, through spline connections 20 in order that the rocking movement of the arms 15 and 16 may be transmitted to the respective torsion springs 18 and 19. A bearing block 21 is secured to the frame member 10 and is provided with journal members 22 within which the torsion springs 18 and 19 are journaled. The remote ends of the springs 18 and 19 are splined at 23 within anchor brackets 24 which are carried by an anchor block 25, secured to the frame member 10.

As will be seen in Figure 2, the spline portion of the torsion spring 18 extends beyond the arm 15 and carries an arm 26 which is splined thereto and secured in position by means of a threaded cap 27 which is secured to the end of the spring 18. Arm 26 extends downwardly and is received within a vertical slot 28, formed in an upper extension 29 of a block 30 which is slidably mounted within an elongated chamber 31, formed by a cylindrical housing 32. The housing 32 is formed with a flange 33 which is adapted to be secured to the frame member 10 and serves as a cylinder within which pistons 34 are slidably received. The pistons 34 are secured to block 30 by means of rods 35, a bearing sleeve 36 being provided, if desired, between the housing 32 and the block 30. By-passes 37 restrict the flow of fluid between opposite sides of the respective pistons 34, thus serving as a cushioning or shock absorbing mechanism. The passages 37 may be provided with adjusting means 38 in order that the effectiveness of the shock absorbing mechanism may be controlled. A cap 39 is provided

30 35 40 45 50 55

for the outer end housing 32, being secured thereto in a suitable fashion and provided with a lug 40 which serves as an abutment to limit the outward sliding movement of block 30 and, correspondingly, the excessive collapse of the front end of the vehicle in case of a failure of the torsion rods 18 and 19.

In the modification shown in Figures 4, 5, 6 and 7, the wheel 11 is independently mounted 10 on the frame 10. As before, the wheel 11 is adapted to be mounted on the cylinder 12 which is connected to the steering knuckle 13. This steering knuckle 13 is held in the bifurcations 17 of the arms 41 and 42 by the pivot pins 14.

15 As shown in Figure 7, one end of the arm 41 is adapted to be secured to the bushing 44 which receives the spline section 20 of the torsion spring 18. The bushing 44 is adapted to receive the tapered roller bearing 45, the inner race 46 of which is suitably secured thereto. The outer race 47 is secured to the bearing housing 48 which is carried by the bearing block 21 which is secured to the frame 10. The roller bearing 45 is held in position by means of the spacing ring 52, and the flanged collar 49 which is secured to the bearing housing 48. The collar 49 is grooved to receive a suitable packing material 50, thus keeping dust or other harmful substances out of the roller bearing 45. The spacing ring 52 and the inner race 46 of the roller bearing 45 are secured to the bushing 44 by means of the threaded lock nut 51 which is adapted to fit the threaded section of the bushing 44.

15 The anchor block 25 is formed with the bifurcations 53 and 54 which are adapted to receive the remote end of the torsion spring 18. A spline section 23 of the torsion spring 18 is received in the bifurcation 54 which acts as an anchor bracket to secure the torsion spring 18 to the frame 10 through the anchor block 25. Beyond the spline section 23 lies an extension 55 which is journalled in the bifurcation 53 and which is secured thereto by means of the lock nut 59, which is received by the threaded end 45 of the extension 55.

45 The arm 41 extends rearwardly, terminating in a journal member 56 by means of which it is journalled to the frame 10. The journal member 56 houses a roller bearing 57 which is journalled on the extension 55 of the torsion spring 18. A spacing ring 58 positions the roller bearing 57, and in conjunction with the bifurcations 53 and 54 acts to prevent axial motion thereof.

55 A circular opening 60 is formed on the arm 41 to facilitate the removal of the torsion spring 18 in case of failure thereof. In normal operation the opening 60 is closed by means of a cover plate 61 suitably secured to the arm 41.

It will be seen that the invention provides for greater vertical front wheel movement than in existing designs, and by means of the shock absorbing mechanism augments the action of the torsion bars. It further prevents excessive collapse of the front end of the vehicle in case the torsion rods fail. The modified form of the invention shown in Figs. 4-7 further provides a more rigid structure characterized by greater stiffness in a forward and rearward direction. 10 In addition this structure facilitates the removal and replacement of the torsion spring 18 upon failure thereof.

I claim:

1. An independent wheel mounting comprising a vehicle frame, a wheel mounting member, spaced arms journaled at one end on the wheel mounting member, whereby vertical movement of the wheel mounting member with respect to the frame is permitted, a bushing on the other end of at least one of the arms journaled to the frame, a torsion spring member splined to the bushing on the end of at least one of the arms, rearward extensions on the arms, and means to journal the said extensions on the frame coaxial with the journal of the said respective arms on the frame. 15

2. An independent wheel mounting comprising a vehicle frame, a wheel mounting member, spaced arms journaled at one end on the wheel 30 mounting member, whereby vertical movement of the wheel mounting member with respect to the frame is permitted, a bushing on the other end of at least one of the arms, a tapered roller bearing mounted on the bushing and journaled 35 to the frame, a torsion spring member splined to the bushing on the end of at least one of the arms, rearward extensions on the arms, and means to journal the said extensions on the frame coaxial to the journal of the said respective arms on the frame. 40

3. An independent wheel mounting comprising a vehicle frame, a wheel mounting member, spaced arms journaled at one end on the wheel mounting member, whereby vertical movement 45 of the wheel mounting member with respect to the frame is permitted, a bushing on the other end of at least one of the arms, a tapered roller bearing mounted on the bushing and journaled to the frame, a torsion spring member splined 50 to one end thereof to the bushing on the end of at least one of the arms, means to mount the other end of the torsion spring on the frame, rearward extensions on the arms, a rearwardly extending element on the torsion spring member, 55 and means to journal the extremity of at least one of the arm extensions on the torsion spring.

PHILIP E. MATTHEWS.
